US0D1092465S

(12) **United States Design Patent** (10) **Patent No.:** **US D1,092,465 S**
(45) **Date of Patent:** **** Sep. 9, 2025**

(54) **PORTABLE DISPLAY DEVICE**

- (71) Applicant: **Apple Inc.**, Cupertino, CA (US)
- (72) Inventors: **Jody Akana**, Los Altos Hills, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendorfer**, San Francisco, CA (US)

- (73) Assignee: **Apple Inc.**, Cupertino, CA (US)

- (**) Term: **15 Years**

- (21) Appl. No.: **29/883,372**

- (22) Filed: **Jan. 27, 2023**

Related U.S. Application Data

- (63) Continuation of application No. 29/715,411, filed on Dec. 2, 2019, now Pat. No. Des. 976,897, which is a continuation of application No. 29/596,995, filed on Mar. 13, 2017, now Pat. No. Des. 868,775, which is a continuation of application No. 29/555,136, filed on Feb. 18, 2016, now Pat. No. Des. 781,285, which is a continuation of application No. 29/480,501, filed on Jan. 27, 2014, now Pat. No. Des. 750,065, and a continuation of application No. 29/465,780, filed on Aug. 30, 2013, now Pat. No. Des. 750,062, said

application No. 29/480,501 is a continuation of application No. 29/437,117, filed on Nov. 13, 2012, now Pat. No. Des. 699,719, said application No. 29/465,780 is a continuation of application No. 29/432,444, filed on Sep. 14, 2012, now Pat. No. Des. 689,482, which is a continuation of application No. 29/384,911, filed on Feb. 4, 2011, now Pat. No. Des. 669,468, said application No. 29/437,117 is a continuation of application No. 29/382,846, filed on Jan. 7, 2011, now Pat. No. Des. 670,692, said application No. 29/384,911 is a continuation-in-part of application No. 29/382,846, filed on Jan. 7, 2011, now Pat. No. Des. 670,692.
